UNITED STATES PATENT OFFICE.

GEORGE G. POWERS, OF LOS ANGELES, CALIFORNIA.

HYPODERMIC SYRINGE.

1,317,314.

Specification of Letters Patent. Patented Sept. 30, 1919.

Application filed October 15, 1918. Serial No. 258,132.

To all whom it may concern:

Be it known that I, GEORGE G. POWERS, a citizen of the United States, residing at Los Angeles, in the county of Los Angeles, State of California, have invented new and useful Improvements in Hypodermic Syringes, of which the following is a specification.

This invention relates generally to hypodermic syringes and more particularly to that kind of hypodermic syringe shown and explained in my Letters Patent No. 1,217,630, dated February 27, 1917, and in an application copending herewith Serial No. 219,300, filed February 26, 1918.

It is a general object of this invention to provide improved construction for hypodermic needles; and the detailed objects and features of the invention will be best understood from the following detailed description of a preferred form of hypodermic needle construction embodying the invention, reference for this purpose being had to the accompanying drawings in which—

Figure 1 is a longitudinal sectional view showing a complete hypodermic syringe, said view being about twice the size of the usual syringe; Fig. 2 is an enlarged detail of a part of the construction shown in Fig. 1; Fig. 3 is a sectional detail showing a slight modification of form; and Fig. 4 is a sectional detail showing how the ordinary needle may be mounted upon my hypodermic syringe.

The present improved form of syringe is adapted to take either the ordinary form of needle shown in Fig. 4 (a needle provided with a cap which screws onto a nipple on the forward end of the syringe body) or to take that form of hypodermic needle which is equipped with a mounting collar, as shown in Figs. 1, 2 and 3. And in taking this last mentioned form of hypodermic needle, the construction has features of advantage which will be hereinafter pointed out.

The syringe may comprise a barrel 10 having suitable handles 11, and a plunger 12 works in the barrel, the plunger being provided with a suitable handle 13. The lower or inner end of the plunger may be hollow as shown at 14 (and as generally described in my said issued patent). For the purposes of facilitating cleaning of the hol-

low 14, I now make the end of the plunger, 5 as shown at 12^a, screw-threadedly separable from the body of the plunger 12^b; so that the part 12^a may be removed for cleaning out the hollow 14. The hollow 14 is provided for the purpose of accommodating the 6 inner end 15^a of a double ended needle 15. A syringe provided with a hollow plunger may take either a single ended or a double ended needle.

The forward end of the syringe barrel is 6 provided with a somewhat reduced (but still comparatively large) portion 16 which has screw threads 17; and a cap 18 screws upon these screw threads; the function of the cap being to hold the needle 15 in place. 7 Now in the specific form of syringe described in my said co-pending application I have shown the reduced portion 16 as being somewhat conical in formation and extending down to a small end, said small 7 end forming the bearing surface against which one end of needle mounting collar 20 is pressed. In the specific form now here described, instead of making this portion 16 conical, I provide it with an extending 8 nipple 21 whose outer end provides the seat against which one end of the mounting collar 20 is pressed, the other end of the mounting collar being pressed against by the inner cavity surface 22 of the cap 18. Now 9 this inner cavity surface of cap 18 is preferably substantially conical in its configuration, so that all parts of the cavity (including the screw threads at 17) within the cap 18 are larger than the small end in 10 which collar 20 is seated and, specifically, are substantially larger than the nipple 21 whose end is of substantially the same size as the smaller end of the cavity. This provides that when the collar is expanded by 11 reason of longitudinal compression, and even if that expansion causes the periphery of the collar to bear against the inner wall of the cap, the mounting collar and the 12 needle cannot become bound in the cap, because the conical form of the cavity always allows the mounting collar to be easily moved out of the cap. This is an important 13 feature of this specific form of syringe; and this feature appertains whether the mounting 14 collar 20 has an exterior ring or coating of 15 hard metal as indicated at 20^a in Fig. 2 or 16 whether the mounting collar, as shown at

22 in Fig. 3, is merely a globule of soft metal. In the case shown in Fig. 3, using that form of mounting collar, I prefer to make the smaller inner end of the cap cavity a round surface as indicated at 22^a, so that the globule of soft metal may bed against that surface more or less spherically; and this form of cap cavity may be used also for the form of mounting collar 10 shown in Fig. 2—may be used universally with any of the different forms of mounting collar. And the conical form of the cap cavity is particularly efficacious in connection with the soft mounting collar, as shown 15 in Fig. 3, because the conical side walls at 22^b then become the limiting means for limiting the amount of lateral expansion of the mounting collar; and at the same time the mounting collar is easily moved out of 20 the cap when the cap is removed from the syringe. Limiting the lateral expansion of the mounting collar (of any form) causes it to compress tightly and form a tight joint around the needle, when the collar is 25 compressed longitudinally.

This feature of the non-binding of the mounting collar and needle in the cap—the conical form of the cap cavity—is also explained and set forth in my said copending 30 application; but the adaptation of the syringe to take either the form of needle shown in Figs. 1, 2 and 3, or that shown in Fig. 4, is peculiar to the syringe shown in this application. The nipple 21, instead of 35 being preferably made integrally with the part 16, is preferably made separate from that part and screw threaded into it, as is well shown in the drawings, so that if the nipple should break off it can be easily removed from the syringe and replaced by the new one. This nipple 21 is of a standard 40 size adapted to take the ordinary form of hypodermic needle as indicated at 15^c in Fig. 4, being that form which has a cap 15^d 45 adapted to screw upon the nipple 21. And the base of the nipple is preferably enlarged at 21^a so that, if it breaks, it will do so at the base of the smaller outer portion, leaving the base part projecting from the part 50 16 where it is easily engaged with a tool and easily removed.

Having described a preferred form of my invention, I claim:

1. In a hypodermic syringe, a barrel with an orifice at its end, a projecting screw-threaded nipple through which the orifice extends, screw threads on the barrel at the base of the nipple substantially larger than the nipple, and a hollow cap adapted to fit over the nipple and screw upon said screw threads.

2. In a hypodermic syringe, the combination of a barrel with an orifice at its end, a nipple at the end of the barrel through which nipple the orifice extends, said nipple being externally screw-threaded and adapted to take the ordinary "cap-type" needle; the end of the barrel having at the base of the nipple a screw thread substantially larger than the nipple, and a hollow cap adapted to screw upon said screw threads and to inclose the nipple, said cap having an end perforation to pass a needle and adapted to hold the mounting collar of the needle against the end of the nipple.

3. In a hypodermic syringe, the combination of a barrel with an orifice at its end, a nipple at the end of the barrel through which nipple the orifice extends, said nipple being externally screw-threaded and adapted to take the ordinary "cap-type" needle; the end of the barrel having at the base of the nipple a screw thread substantially larger than the nipple, and a hollow cap adapted to screw upon said screw threads and to inclose the nipple, said cap having an end perforation to pass a needle and adapted to hold the mounting collar of the needle against the end of the nipple.

4. In a hypodermic syringe a barrel, and a plunger therein comprising two separable parts, the end part of the plunger fastened within the barrel being longitudinally hollow and separable from the other part.

In witness that I claim the foregoing I have hereunto subscribed my name this 2d day of October, 1918.

GEO. G. POWERS.
